RAYMOND W. ERWIN, OF FREMONT, OHIO, ASSIGNEE TO NATIONAL CARBON COMPANY,
OF CLEVELAND, OHIO, A CORPORATION OF NEW JERSEY.

DOWEL CONNECTION.

1,136,111.

Specification of Letters Patent.

Patented Apr. 20, 1915.

Application filed September 29, 1913. Serial No. 792,360.

To all whom it may concern:

Be it known that I, RAYMOND W. ERWIN, a citizen of the United States, residing at Fremont, in the county of Sandusky and 5 State of Ohio, have invented a certain new and useful Improvement in Dowel Connections, of which the following is a full, clear, and exact description.

In a common form of dry battery, the 10 binding posts consist of a screw and a knurled nut, one particular form having a screw retained in a hole in the carbon rod.

My invention relates to this latter dowel type. The carbon electrode surrounded by 15 an exciting mix is packed in a zinc container and closed with a sealing layer. Various forms of carbon electrodes have been used, among which a corrugated electrode has been found to be particularly 20 advantageous. These may either be molded or forced through a hydraulic machine, the latter being the preferable method on account of its cheapness. If a dowel pin connection is used, and the corrugated electrode is 25 placed flush with or projecting from the seal, the sealing material will not flow evenly between the corrugations, and will present a poor appearance.

It is the object of my invention to provide 30 a dowel terminal that permits the use of a corrugated electrode and at the same time secure a neat seal with the top layer of pitch or analogous material.

Referring to the drawings: Figure 1 is a 35 cross sectional view of the upper portion of a dry battery showing the connection. Fig. 2 is an isometric view of the hexagonal nut and corrugated electrode.

Referring to the drawings, the carbon electrode 1 is surrounded by the usual exciting- 40 depolarizing material 2 consisting of carbon, and pyrolusite moistened with electrolyte solution. The mix is placed in the zinc container 3 having a bibulous lining 4 and closed by a seal 5 consisting of various layers such as a corrugated disk 6, a layer of sand 7, and a top seal of pitch 8. The carbon electrode 1 has a hole 9 therein with an 45 irregular space usually formed by drilling slanting holes 9' at the bottom. The extremity of a dowel 10 has a head portion 11 which is held in the electrode by pouring 50 into the hole 9 a suitable molten metal 12 such as type metal. Upon solidifying the

dowel is held firmly in place by the clamping nut 13.

In dowel pin connections with smooth carbon rods, the top of the seal has been made flush with the top of the rod. If this process is followed out with a corrugated 60 rod, the seal will not flow evenly in the corrugations and a poor seal results. If the seal is made deeper so as to flow over the top of the rod, it will not make a smooth fit with the circumference of the hexagonal nut of 65 the dowel screw. It is, of course, impossible to let the seal flow over the top of the hexagonal nut as the connecting wire is to be clamped thereagainst. In order to obtain a good seal of neat appearance, I shorten the 70 carbon electrode so that the top will reach about $\frac{1}{4}$ inch below the top of the seal. After the dowel pin has been attached to the electrode by means of the type metal, a hexagonal nut 13 is screwed on so as to hold the 75 connection tightly in place and produce a good contact between the type metal and the electrode. It is in the special construction of this clamping nut and arrangement of the seal that my improvement lies. In 80 stead of the usual thin nut, I use one with a circular projection 14 and pour the seal on approximately flush with the end projection as shown in the drawing. The seal covers up the polygonal periphery of the nut and 85 makes good contact with the round barrel of projection 14. The barrel 14 may be separate from the nut, but the construction shown is preferable.

In addition to the better appearance, a 90 more perfect seal is formed by my improvement.

Having described my invention, what I claim is:

1. In a dry cell, a carbon electrode having 95 a cavity in one end, a dowel in the cavity having means to retain it therein, a clamping nut having a flange and a cylindrical boss threaded on the dowel, said nut abutting against the end of the electrode, a mix 100 around the electrode, a receptacle to contain the mix, a seal extending from the receptacle to the boss whereby the end of the electrode and flange of said nut are covered by said seal.

2. In a dry cell, a carbon electrode, a metal sheath in one end of the electrode having a 105 projecting lug, a dowel in said sheath, a nut

having a flange and a cylindrical boss threaded on the dowel to bind the sheath tightly in the electrode, a mix around the electrode, a receptacle for the mix and a seal in the end of the receptacle extending above the flange of said nut to contact with the said boss.

In testimony whereof, I hereunto affix my signature.

RAYMOND W. ERWIN.
